US00D695411S

(12) **United States Design Patent**
Swern et al.

(10) **Patent No.:** US D695,411 S
(45) **Date of Patent:** ** Dec. 10, 2013

(54) **TEETHING DEVICE**

(71) Applicants: **Dynamic Mouth Devices, L.L.C.**,
Boonton, NJ (US); **Michael Swern**,
Boonton, NJ (US); **Salvatore Napoli**,
Florham Park, NJ (US)

(72) Inventors: **Michael Swern**, Boonton, NJ (US);
Laura Bardach, Boonton, NJ (US);
James Geduldig, Boonton, NJ (US);
Salvatore Naopoli, Florham Park, NJ
(US)

(73) Assignee: **Dynamic Mouth Devices, L.L.C.**,
Boonton, NJ (US)

(**) Term: **14 Years**

(21) Appl. No.: **29/455,992**

(22) Filed: **May 28, 2013**

Related U.S. Application Data

(62) Division of application No. 29/433,626, filed on Oct. 2, 2012, now Pat. No. Des. 685,485, which is a division of application No. 29/399,283, filed on Aug. 11, 2011, now Pat. No. Des. 671,223.

(57) **CLAIM**

The ornamental design for a teething device, as shown and described.

DESCRIPTION

FIG. 1 is a perspective view of a teething device showing our new design;

FIG. 2 is a perspective view of the teething device of FIG. 1; FIG. 3 is front elevational view of the teething device of FIG. 1;

FIG. 4 is a rear elevational view of the teething device of FIG. 1;

FIG. 5 is a right side elevational view of the teething device of FIG. 1, the left side elevational view being a mirror image of the right side elevational view; and,

FIG. 6 is a top plan view of the teething device of FIG. 1, the bottom plan view being a mirror image of the top plan view. The broken lines illustrate portions of the teething device which form no part of the claimed design.

1 Claim, 4 Drawing Sheets
